United States Patent Office

Des. 188,207
Patented June 14, 1960

188,207

DAVIT REEL OR THE LIKE

Walter Uebelhoer, Snyder, N.Y., assignor to Marwal
Products Corporation, Buffalo, N.Y.

Filed May 25, 1959, Ser. No. 56,049

Term of patent 14 years

(Cl. D41—1)

FIG. 1

FIG. 2

FIG. 3

FIG. 4

Fig. 1 is a top perspective view of a davit reel or the like, showing my new design;

Fig. 2 is a side elevation thereof;

Fig. 3 is an end elevation thereof; and

Fig. 4 is a bottom plan view thereof, on a reduced scale.

The side not shown is substantially identical to that shown in the drawings.

I claim:

The ornamental design for a davit reel or the like, substantially as shown and described.
